UNITED STATES PATENT OFFICE.

FRED D. FOWLER, OF WATERTOWN, MASSACHUSETTS, ASSIGNOR TO HOOD RUBBER COMPANY, OF WATERTOWN, MASSACHUSETTS, A CORPORATION OF MASSACHUSETTS.

BEAD-COVERING APPARATUS.

Application filed December 14, 1923. Serial No. 680,698.

To all whom it may concern:

Be it known that I, FRED D. FOWLER, a citizen of the United States, and resident of Watertown, in the county of Middlesex and 5 State of Massachusetts, have invented certain new and useful Improvements in Bead-Covering Apparatus, of which the following is a specification.

My invention relates to improvements in 10 machines designed to apply rubberized covering strips to bead cores such as are incorporated in the edges of open-bellied, or double-tube pneumatic tires, and is herein shown as embodied in apparatus for applying such strips to cores intended for use in 15 the clincher type of tire.

The invention aims to provide a simple, economical and durable form of apparatus, utilizing but little floor space, which will 20 smoothly and evenly apply the fabric to a bead core of endless form, the core being maintained during such operation in a horizontal plane.

With these and other objects in view, the 25 invention includes the novel features of construction and arrangement and combination of parts hereinafter described, and particularly defined by the appended claims.

An embodiment of my invention is illustrated 30 in the accompanying drawings, in which:—

Figure 1 is a plan view of an apparatus or machine constructed in accordance with my invention.

Fig. 2 is a front elevation.

Fig. 3 is a section through the first set of operating rolls, and

Fig. 3^a an enlarged sectional view of the core and strip at the first operating position.

Fig. 4 is a section through the second set of rolls, and

Fig. 4^a an enlarged detail of the bead and strip.

Fig. 5 is a section through the third set of operating rolls, and

Fig. 5^a an enlarged detail of the core and strip, and

Fig. 6 is a plan view of Fig. 5.

Fig. 7 is a detail section through the travelling band and associated rolls, with the driving means therefor.

Referring by reference characters to these drawings, the numeral 1 designates a supporting table mounted upon standards 1^a (shown broken away for convenience) so as

to be at a height suitable for the operator. Mounted at a suitable point upon the table is a guide trough 2, by which the covering strip or band of rubberized fabric 3 is received from any suitable source and guided to the juxtaposing or assembling devices, passing first around the idle roll 4 and thence up around the idle roll 5 flanged to prevent fabric from slipping due to any irregularity in bead where it meets the bead core 6 which is properly positioned thereon. This bead core is of substantially triangular formation, as shown, and having one flat and one convex face meeting at an acute angle, as indicated at 6^a, and having the third side 6^b (opposite said acute angle) of concave form. I have found that advantageous results are secured by juxtaposing the bead core and fabric strip in such a manner that said edge 6^a will be pressed against the strip at approximately the center line thereof and with one face of the bead held vertical, and thereafter the fabric strip manipulated in the manner described below.

To this end I provide a guide roll 7 which is journaled on a vertical axis directly above the axis of roll 5 and with its lower end spaced far enough above the surface of roll 5 to permit free passage of a splice in the fabric. To maintain the fabric strip in proper position on roll 5, it is provided with flanges, and a simple form of roll construction providing these, is to make the roll body in the form of a cylinder and provide heads 5^a having annular opposed grooves into which the ends of the cylinder engage; the peripheries of the heads projecting beyond the roll surface and forming the aforesaid flanges.

Rolls 4 and 5 are preferably journaled by anti-friction bearings on shafts 4^x and 5^x carried by standards 8 rising from the table 1, and roll 7 is likewise journaled by anti-friction bearings on a stub axle 7^x supported by the curved upper end of a bracket 9 which may be conveniently secured to projected ends of shafts 4^x and 5^x by nuts x.

Cooperating with rolls 5 and 7 is a presser roll 10 which is journaled by anti-friction bearings on a stub shaft 10^x carried by a bracket member 11 articulated upon a support 12 and provided with an operating handle 10^y. Bracket 11 is acted upon by springs 13 which, in one position, tend to swing the roll 10 towards the rolls 5 and 110

- 7, causing the roll to press the bead into the angle formed by rolls 5 and 7. When the bead core is to be inserted the operator grasps handle 10^a and moves it in the proper 5 direction against the tension of the springs, and if the movement is continued far enough the upper ends of the springs are carried past the dead center and the presser roll 10 held in ineffective position.
- 10 Said presser roll 10 has a grooved periphery forming two walls or faces 10^a and 10^b, one of which, 10^a is curved or convex to conform to the concave upper face of the bead, while the other is convex, being struck 15 from the point of the swinging arm which carries this roll, so that as the roll is swung to and from operative position, this face will clear the side face of the bead. The wheel also has a groove at the point 20 where these faces converge to receive the convex edge at the heel of the bead.

The bead, having been superposed on the fabric strip and pressed thereagainst by the roll or wheel 10, it then passes between two 25 pairs of successively coacting roller members, at which time the fabric is folded about the bead, as hereinafter described.

Said pairs of coacting rolls comprise two lower grooved rolls 14 and 15, which are 30 mounted on shafts 14^x and 15^x provided with sprockets 14^y and 15^y fast thereon around which pass sprocket chain 16 which meshes with sprocket 17 carried by drive shaft 17^a to which power may be applied 35 in any suitable manner, and which is exemplified by the hand crank 17^b.

The roll 14 has a grooved periphery providing two faces 14^a and 14^b, the former of which is flat or straight, and conforms to the 40 flat side of the bead and is disposed in alignment with the bead engaging portion of the periphery of roll 7, while the other face, 14^b, is concave to fit the convex face of the bead or bead core. Mounted above 45 this roll 14, and cooperating therewith, is a roll 18 having a convex periphery which is designed to coact with the concave face of the bead core and press the same into the groove of the roll 14, thereby drawing 50 the fabric covering up over, and causing it to be pressed firmly against the respective sides of the bead core, as shown in Figs. 4 and 4^a. The roll 18 is preferably journaled on anti-friction bearings on a shaft carried 55 by a fork member 18^a which is carried by a supporting arm 19 carried by a bracket member 20, which is articulated on a support 21 and is under the tension of springs 22 which tend, in one position of the arm 60 19, and as shown in Fig. 4, to press the roll 18 against the bead core. Fork 18^a has an extended shank which carries a handle 18^b by which arm 19 may be swung to move the presser roll away from the roll 65 14, which movement may be continued far

enough to swing the upper end of the spring past the dead center and thereby hold the roll 18 out of operative position.

As shown in Fig. 4, the fabric strip has been applied to two faces of the bead core, 70 leaving the projecting flaps or free edge portions 3^a and 3^b respectively. The next operation is to fold the flap or portion 3^a across the concave face of the bead and press it there-against with its edge overlapping the 75 base or inner portion of the flap 3^b. To accomplish this the bead core with its fabric covering applied as aforesaid, is led to the roll 15 which has its periphery provided with a groove 15^a of the same shape as the 80 groove in the periphery of the roll 14, and cooperating with this is a rotary presser member or roll 23 which has its periphery provided with a convex portion adapted to press the flap 3^a onto the concave side of 85 the bead and unite it firmly thereto, and also has a flared side wall which cooperates with a stationary presser member 24 to press the free edges of the flaps together. This member 24 is preferably in the shape 90 of a curved bar or strip of resilient sheet metal, having a portion bolted or otherwise secured to the bearing brackets of the rolls 14 and 15, as shown. The said roll 23 is, 95 like the roll 18, mounted in a fork and spring-pressed toward roll 15, and provided with a manipulating handle enabling this roll to be manipulated in exactly the same manner as is the roll 18 heretofore described, 100 but act at an angle in relation to its companion roll 15, and as the arrangement of pivoted mounting and spring connection is substantially the same, repetition of the description is deemed unnecessary.

As hereinbefore stated, I have found that 105 the bead cores can be most effectively covered if supported in a horizontal position, and to this end I provide at the back of the machine an endless supporting band 25, having a surface designed to coact with the tacky material employed for bead construction. This band 25 passes over end guide rolls 25^a and 25^b, and I prefer to so 110 mount the belt that the returning or idle portion will lie directly under, and be protected by the work supporting portion, as shown in detail in Fig. 7, and to this end I pass the belt over the rollers 25^a, 25^d and 25^e, as shown in said Fig. 7. The conveyor belt travels at a slightly higher speed than 115 the bead does through the forming rollers, so that the belt is, at all times, pulling the bead into firm contact with the idle roller 30. This serves to maintain the bead in substantially a constant position in leaving the second operating roll in order to hold 120 a uniform margin. This faster speed of the conveyor also insures slack at the entering end of the machine, which prevents stretching of the beads.

125

130

Clincher beads, being extensible, are of course, flexible, and co-operating with the rear edge of the travelling band is a stationary guard 26 which causes the bead to be deflected into the form of an elongated oval, by which means the machine may be relatively shallow. In addition to the efficiency in covering, the advantage of holding the bead in horizontal position and in the shape of an elongated ellipse, is that not only can the operation of the covering rollers be observed by the operator, but the covered portion of the strip of the bead, as it passes along the conveyor, is equally within range of the eye of the operator and thus he can watch for and detect any defects. The belt is driven from sprocket 27 carried by shaft 17^a, through the intermediary of a sprocket chain 28 and sprocket 29 on the shaft of the roller 25^e, which helps support the belt 25. A roll 30 journaled on a vertical axis, receives the covered bead as it issues from between the rolls 15 and 23, this roll having a horizontal supporting flange 30^a upon which the bead rests. Guide rolls 31 are provided at the opposite end of the machine, between which the bead passes, and by which it is directed between the rolls 5, 7 and 10, hereinbefore described.

At the first operating roll 14 there is a stationary guide member 32 formed with or secured to the bracket 18^a in which said roll is journaled. This member extends alongside the roll and lengthwise of the fabric and bead. This guide is to prevent the long flap of the fabric, i. e., the flap lying on the operator's side of the bead, from accidentally folding over and touching the shorter flap of fabric on the far side of the bead until such time that this shorter flap has been properly rolled down into the concave face of the bead by the second operating roll 23.

Having thus described my invention, what I claim is:—

1. In apparatus for covering beads, a cylindrical roller, means for guiding a covering strip thereto, a roller journaled on an axis perpendicular to the surface of said first named roller, and having its end spaced therefrom to permit passage of the strip, and a presser roller located in a plane substantially bisecting the angle formed by the adjacent surfaces of said first and second rollers, means for yieldingly pressing said presser roller towards said first named two rollers, said presser roller having a grooved periphery and said second roller being positioned with its bead guiding portion approximately centrally of the width of the strip.

2. In apparatus for covering beads, a cylindrical roller having guide flanges,

means for directing a covering strip upon said roller between said flanges, a positioning roller journaled on an axis perpendicular to the axis of said cylindrical roller, and having its end juxtaposed to the surface of said cylindrical roller but spaced therefrom, guiding means for directing a bead core into the angle formed by said rollers and upon the fabric strip, and a presser roller journaled in an inclined plane and having a grooved periphery to coact with the bead, and means for pressing said pressing roller against the bead.

3. In apparatus for covering endless bead cores, means for guiding a covering strip, means for pressing a bead core onto said strip, succeeding means for folding the strip about the bead, and an endless supporting band over which the intermediate portion of said bead passes, with means for moving said supporting band.

4. In apparatus for covering endless bead cores, means for guiding a covering strip, means for pressing a bead core onto said strip, succeeding means for folding the strip about the bead, and an endless supporting band over which the intermediate portion of said bead passes, with means for moving said supporting band, and a guide wall associated with said band for deflecting said bead into the form of an elongated oval.

5. In combination in apparatus for covering endless bead cores, means for applying a fabric strip to the core, and means for imparting movement to the portion of the endless bead core which lies outside of said applying means to create slack at the feeding-in end of the applying means, substantially as described.

6. In combination in apparatus of the class described, means for directing a bead core and fabric covering strip into contact with an apex of the bead pressed against the central portion of the strip, a pair of rolls by which the covering strip is turned up at its side edges to embrace the bead core, and leave flaps of said strip projecting above said core, a guard arranged adjacent said rolls to keep the said flaps separated, and a second pair of rolls for completing the wrapping of the covering strip about the bead core, substantially as described.

7. In apparatus for covering endless bead cores, means for juxtaposing a covering strip and bead core and folding the former about the latter, a movable support over which the intermediate portion of the bead passes, and a guide member associated with said wall for deflecting said bead into the form of an elongated oval.

In testimony whereof, I affix my signature.

FRED D. FOWLER.
